UNITED STATES PATENT OFFICE

158,607

ELECTRIC HAIR DRIER OR SIMILAR ARTICLE

Samuel L. McNair, Boston, and Clarence E. Wyman, Brockton, Mass.

Application January 17, 1948, Serial No. 143,853

Term of patent 3½ years

(Cl. D86—10)

To all whom it may concern:

Be it known that we, Samuel L. McNair and Clarence E. Wyman, citizens of the United States of America, residing, respectively, at Boston, in the county of Suffolk, in the Commonwealth of Massachusetts, and at Brockton, in the county of Plymouth, in said Commonwealth, have invented a new, original, and ornamental Design for an Electric Hair Drier or Similar Article, of which the following is a specification, reference being had to the accompanying drawing, forming a part thereof, in which:

Fig. 1 is a perspective view of an electric hair drier showing our new design.

Fig. 2 is a front elevational view thereof.

Fig. 3 is a top plan view.

Fig. 4 is a side elevational view corresponding to the disclosure in Fig. 1; and

Fig. 5 is a view of the side opposite to that in Fig. 4.

We claim:

The ornamental design for an electric hair drier or similar article, substantially as shown.

SAMUEL L. MCNAIR.
CLARENCE E. WYMAN.
